(57) CLAIM

The ornamental design for a golf training mat, as shown and described.

DESCRIPTION

FIG. 1 is a top perspective view of a golf training mat, showing our new design;

FIG. 2 is a top plan view thereof;

FIG. 3 is a bottom plan view thereof;

FIG. 4 is a right-side elevation view thereof, the left-side elevation view being a mirror image thereof; and,

FIG. 5 is a front elevation view thereof, the rear elevation view being a mirror image thereof.

The evenly spaced broken lines shown in the drawings depict portions of the golf training mat that form no part of the claimed design.

The dash-dot-dash broken lines shown in the drawings denote the boundaries of the claim and form no part thereof.
